UNITED STATES PATENT OFFICE.

MORRIS MARTIN, OF MALDEN, MASSACHUSETTS, ASSIGNOR TO GEORGE W. GREGORY, TRUSTEE, OF BOSTON, MASSACHUSETTS.

FLUID-GAGE.

SPECIFICATION forming part of Letters Patent No. 794,679, dated July 11, 1905.

Application filed November 28, 1904. Serial No. 234,483.

To all whom it may concern:

Be it known that I, MORRIS MARTIN, a citizen of the United States, and a resident of Malden, in the county of Middlesex and State of Massachusetts, have invented an Improvement 5 in Fluid-Gages, of which the following description, in connection with the accompanying drawings, is a specification, like characters on the drawings representing like parts.

This invention has for its object the production of a novel gage for indicating the quantity of fluid—as gasoline, oil, or water—in a tank wherein the fluid is not usually to be subjected to pressure.

The novel gage to be herein described and claimed comprises a head open at its center for filling and having a depending tube provided with a rock-shaft carrying a magnet, a compass-box provided with a magnetic needle, the bottom of the compass-box when in its operative position closing the filling-opening of the head, and a float inside said tube coacting with and turning said rock-shaft and magnet, the latter rotating the magnetic needle in unison with it.

I have provided the head with a telltale which is moved by the magnet as the tank is being filled, the magnetic needle at such times being removed from above the filling-opening, the compass-box then occupying its inoperative position, said telltale serving temporarily to take the place of the magnetic needle to tell when the tank is full, the telltale being carried around with the magnet.

Figure 1 of the drawings is a sectional view of part of a tank with my novel gage attached thereto, the dotted lines showing the compass-box in its inoperative position. Fig. 2 is a top view of Fig. 1. Fig. 3 is a plan view 30 of the top of the head with the compass-box removed. Fig. 4 shows the filling-tube that will be inserted in the filling-opening of the head when the tank is to be filled. Fig. 5 is a section below the line α , Fig. 1. Fig. 6 shows 35 a plug, and Fig. 7 one of the ears of the head. Fig. 8 is a section looking up from the line γ to show the rod c' .

Referring to the drawings, A represents part of a tank of usual construction, the tank

being provided with a curb a , that may be 50 maintained in position by means of a ring-nut a' . The gage comprises a head B, having a central filling-opening b , preferably threaded at its interior, and the head is further threaded at b' to receive the upper threaded end of 55 a tube C, and the head has threads b^2 , by which the head may be connected with the curb. The head is represented as provided with a circular groove b^3 , surrounding the filling-opening, and the upper side of the head is provided with a raceway b^4 , in which is mounted a steel ball b^5 , herein designated as the "telltale," and the bottom of the raceway is provided with a series of vent-holes b^6 , that lead into the groove b^3 , said vent-holes permitting 60 the air in the tank to flow outwardly therefrom as the oil is being filled into the tank through the filling-tube b' , Fig. 4, which when the tank is being filled will be screwed into the threaded part of the filling-opening. 70

The tube C is closed at its lower end by a cap or step c , and near its upper end the tube is provided with a cross-bar c' . (See Figs. 1 and 3.) The cap and bar c and c' constitute 75 bearings for a rock-shaft c^2 , represented as crank-shaped, the lower end c^3 of said crank-shaft being guided in the plate c , the upper end c^4 thereof being extended through a hole in the bar c' , the end of the shaft above said bar having connected therewith by a screw 2 80 a collar 3, and above the collar is mounted, so as to turn with the shaft, a permanent magnet D, shown as of U shape, the magnet being adjustably fixed relatively to the collar and shaft to rotate therewith by a screw 4, 85 the loosening of which permits the adjustment of the magnet with relation to the shaft to insure the correct action of the magnet, as will be described.

The tube is shown as slotted at c^5 , the slot 90 being spirally arranged. Inside the tube is a float E, composed of two thin metallic shells soldered together and provided with a pin e , extended therethrough from one to its opposite side, one end of the pin being extended 95 into the spiral slot c^6 , the pin between the float and its end inside the tube having a hole (see Fig. 5) to embrace loosely the shaft c^2 .

The head is provided (see Fig. 3) with two ears 5, constituting part of a hinge, the other part of the hinge being an ear projecting from the compass-box F, the ear of the compass-box and of the head being united by a pintle 6. The compass-box has a pin 16, on which is mounted a magnetic needle e, that is kept from leaving the pin by a glass e', held in place by a wire ring e''. A packing 7, interposed between the under side of the glass and the shoulder in the compass-box sustaining the glass, prevents water or moisture entering the compass-box.

The compass-box has means to secure the box in its operative position, including a catch f and a pin f'. When it is desired to refill a tank, the compass-box may be turned upwardly into its inoperative position, as shown by dotted lines, Fig. 1, and after screwing the 15 filling-tube into the filling-opening b the gasoline or other fluid may be poured into the filling-tube through the filling-opening, entering the upper end of the float-guiding tube, which has one or more holes 20. If the tank 20 is so exhausted that the float is in the bottom of the tube, the float will commence to rise, the pin e in the slot e' will turn the float, causing it to turn the crank-shaft and rotate the magnet; but as the compass-box is turned or 25 removed from its operative position and the magnet is not exposed the extent to which the tank is filled would not be indicated, and consequently I provide the raceway b' with a tell-tale or piece of metal, as a ball, which is 30 moved in unison with the magnet in the raceway. The top of the head will be marked "1 1/2 4" and be provided with a letter, as "F," to designate "full," and by following the tell-tale with the eye it will act temporarily to 35 40 take the place of the magnetic needle to show the person filling the tank when to stop. The tank having been supplied with gasoline, the compass-box will be put in its operative position, as shown by full lines, Fig. 1, and the 45 bottom of said box will close the filling-hole, the catch holding the compass-box in its operative position. As soon as the compass-box is turned into its operative position the magnetic needle immediately alines itself with the 50 magnet, the south pole of the needle turning into position to be held by the north pole of the magnet.

If it should be desired to employ the gage so far described in a tank where the fluid is 55 maintained under pressure, I may in such event insert a screw-plug 22 (see Fig. 6) in the threaded filling-opening after filling the tank. This plug has a thin flange wide enough to overlap the raceway, and when using this 60 plug the pintle 6, connecting the compass-box with the head, will be drawn and inserted through the upper holes 20 of the ears 5 (see Fig. 7) rather than in the lower holes 21, as shown in the drawings.

65 Having fully described my invention, what

I claim as new, and desire to secure by Letters Patent, is—

1. In a fluid-gage, a head having a filling-opening, a depending tube, a rock-shaft therein provided with a permanent magnet, a float 70 to turn said rock-shaft and magnet, a compass-box sustained at the upper end of said head and closing said filling-opening, and a magnetic needle mounted in said compass-box.

2. In a fluid-gage, a head having a filling-opening, a depending tube, a rock-shaft therein provided with a permanent magnet, a float 75 to turn said rock-shaft and magnet, a compass-box, hinged to said head and provided with a magnetic needle, said compass-box when in its 80 operative position closing said filling-opening.

3. In a fluid-gage, a head having a filling-opening, a depending tube, a rock-shaft therein provided with a permanent magnet, a float 85 to turn said rock-shaft and magnet, a compass-box hinged to said head and provided with a magnetic needle, said compass-box when in its operative position closing said filling-opening, and means to lock the compass-box in its 90 operative position.

4. In a fluid-gage, a head having a filling-opening, and provided with air-vents outside said opening, a depending tube, a rock-shaft therein provided with a permanent magnet, a float 95 to turn said rock-shaft and magnet, a compass-box sustained at the upper end of said head and closing said filling-opening, and a magnetic needle mounted in said compass-box.

5. In a fluid-gage, a head having a central 100 filling-opening provided with screw-threads to receive a filling-tube, a depending tube, a rock-shaft therein provided with a permanent magnet, a float to turn said rock-shaft and magnet, a compass-box sustained at the upper 105 end of said head and closing said filling-opening, and a magnetic needle mounted in said compass-box.

6. In a fluid-gage, a head having a filling-opening and a surrounding raceway, a telltale 110 mounted loosely in said raceway, a depending tube, a rock-shaft therein provided with a permanent magnet, a float in said tube to turn said shaft and magnet, the latter moving the telltale in said raceway as the magnet is turned 115 through the movement of said float.

7. In a fluid-gage, a head having a filling-opening, a depending slotted tube, a crank-shaft sustained loosely in said tube, a permanent magnet carried by said crank-shaft, a 120 float in said tube provided with a pin embracing said shaft loosely and entering the slot of said tube, said float rotating said crank-shaft and magnet as the float is moved by variation of level of fluid in said tank.

8. In a fluid-gage, a head, a depending slotted tube, a crank-shaft sustained therein, the central part of said shaft being located near the inner wall of said tube, a float composed of two hollow cups united at their open ends 130

air and fluid tight, and a pin extended from one side of said float embracing said shaft, the end of the pin entering the slot of the tube and turning said shaft in one or the other direction as the float rises or falls.

5. In a fluid-gage, a head having a centrally-located hollow boss constituting a filling-opening, a depending tube, a shaft in said tube, said shaft having its journals within the circle bounding said filling-opening, a float for turning said shaft, and a U-shaped magnet carried at the upper end of said shaft.

10. In a fluid-gage, a head provided with a vent-opening and a centrally-located hollow

boss constituting a filling-opening, a depending tube, a shaft in said tube, said shaft having its journals within the circle bounding said filling-opening, a float for turning said shaft, and a U-shaped magnet carried at the upper end of said shaft.

20

In testimony whereof I have signed my name to this specification in the presence of two subscribing witnesses.

MORRIS MARTIN.
